UNITED STATES PATENT OFFICE.

JOHN GEHBAUER, OF ST. LOUIS, MISSOURI.

FAN ATTACHMENT FOR LAWN-SWINGS.

1,276,050.

Specification of Letters Patent. Patented Aug. 20, 1918.

Application filed August 8, 1917. Serial No. 185,110.

To all whom it may concern:

Be it known that I, JOHN GEHBAUER, a citizen of the United States, residing at St. Louis, in the county of St. Louis City and State of Missouri, have invented certain new and useful Improvements in Fan Attachments for Lawn-Swings, of which the following is a specification, reference being had to the accompanying drawings.

10 This invention relates to swings, and particularly to a fan attachment for swings.

The general object of the invention is to provide an attachment of this character whereby, while the swing is being operated, 15 the user of the swing will be fanned.

A further object of this invention is to provide a device of this character which may be easily attached to lawn swings of ordinary construction.

20 A further object is to provide a construction of this character in which a rotatable fan is mounted upon the foot board of the swing and pawls are mounted to engage with a ratchet wheel carried by the foot board, the pawls being mounted upon the frame of the swing so that as the body of the swing oscillates, the pawls will alternately engage with the ratchet wheel to thereby rotate the fan.

30 Other objects will appear in the course of the following description.

My invention is illustrated in the accompanying drawings, wherein:

Figure 1 is a side elevation of a lawn 35 swing with my attachment applied thereto;

Fig. 2 is a sectional view on the line 2—2 of Fig. 1 looking downward;

Fig. 3 is a perspective view of the attachment with the parts separated;

40 Fig. 4 is a vertical sectional view through the attachment, a portion of the foot board, and a portion of the base;

Fig. 5 is a fragmentary top plan view of shaft 17 and its pawl and showing in dotted lines a portion of the ratchet wheel.

Referring to these drawings, it will be seen that I have illustrated an ordinary form of lawn swing comprising a base 10 and upwardly extending uprights 11 to which are 50 pivotally connected the depending oscillating bars or supports 12 carrying the body 13 of the swing. This body is provided with the transversely extending foot boards 14 and the base 10 includes a transversely extending brace or cross piece 15.

Attached to the cross piece 15 at a pre-

determined distance are the bearing members 16. Each of these bearing members is flat on one side and is held to the cross piece 15 by screws. Each bearing member is provided with a longitudinally extending socket, the sockets facing toward each other. Rotatably mounted between these bearing members is a shaft 17, which may be square in cross section for the greater portion of its length and is reduced at its ends as at 18, these reduced rounded ends fitting in the sockets and rotating therein. Attached to the shaft 17 are the oppositely directed pawls 19 and 20, these pawls being 65 of the same character and preferably being formed in one piece with the shaft 17, though not necessarily so. These pawls at their ends are each provided with a tooth 21, each tooth being beveled upon its outer face as at 75 22. All of these parts may be of any suitable material, but preferably are of iron or steel.

Disposed through an opening between the foot boards 14 is a rectangular block 23, to 80 which is attached a plate 24. This plate rests upon the slats of the foot board and is held thereto by screws or in any other suitable manner. The upper face of the plate is provided with a ball race concentric 85 to the vertically extending passage 25 through said block or bushing. The lower face of the block is also provided with a ball race. Rotatably mounted in the passage 25 is a shaft section 26, which at one end is 90 provided with the laterally extending flange 27, the under face of which is also provided with a ball race and disposed between this flange 27 and the plate 24 are the ball bearings 28 operating in the corresponding races. 95 The shaft section 26 extends below the block or bushing 23 and this projecting end of the shaft section is square for a portion of its length and beyond this squared portion is circular in section and screw-threaded. 100 Fitting upon the square portion of the shaft section 26 is a ratchet wheel 29, which is held in place by a nut 30 engaging the screw-threads on the lower end of the shaft section 26. Anti-friction balls or other anti-friction 105 bearings 31 are disposed between the ratchet wheel 29 and the adjacent end of the block 23. The ratchet wheel is preferably skeletal in form as illustrated clearly in Fig. 3 and the under face of the ratchet wheel, adjacent its margin, is provided with a plurality of radially projecting ratchet teeth 110

32, one face of each tooth being beveled and all the teeth being beveled in the same direction. The opposite faces of the tooth are not exactly vertical, but slightly inclined outward and downward. These teeth are adapted to be engaged by the detents or teeth 21 on the ends of the dogs or pawls 19.

The upper end of the shaft section 26 is formed with a socket and disposed in this 10 square socket is a rod 33 of any desired length which is held in place by a set screw 34 passing through the flange 27. Carried upon this rod 33 in any suitable position is a rotatable fan comprising a central body 15 35 having radially extending stubs 36, the side faces of which are inclined to the horizontal and attached to these stubs are the fan blades 37 which are also inclined to the horizontal.

20 The operation of this device will be obvious from the drawing. As the body 13 is oscillated back and forth across the bar 15, the teeth on the ratchet wheel 29 will alternately engage the pawls 19 and 20. Thus 25 upon a movement of the body 13 with the ratchet wheel 29 in one direction, the pawl 19 will engage with the teeth and give a rotation to the ratchet wheel and thus to the fan and upon a movement of the body 13 in 30 the opposite direction, the pawl 20 will engage the teeth on that side and give a movement to the fan. Of course after the body has passed the cross bar 15 and the wheel is rotated, the tooth will disengage from the 35 pawl and the body continue its swing the fan being rotated by the impulse given to it by the pawl. The same operation will occur upon the reverse oscillation of the body 13. Thus as the swing is operated and oscillates 40 back and forth across the bar 15, the ratchet wheel will be given intermittent movement in the same direction. As the ratchet wheel is mounted upon ball bearings, the ratchet wheel will continue to rotate after it becomes 45 disengaged from the pawls, so that a nearly continuous movement is given to the fan blades. The body of the fan may be adjusted upon the shaft section 33 to any desired extent. It will be seen that my device is 50 very simple, that it may be readily applied to any common form of garden or lawn swing and that a rotation of the fan will cause a draft of air to be directed toward the user of the swing.

55 It is obvious also that by a slight modification of the mechanism, the fan might be mounted for rotation in a vertical plane instead of a horizontal plane and that many modifications in detail and arrangement of 60 parts might be made, without departing from the spirit of the invention.

It will be noted that the pawls 19 and 20 extend upward and outward in a slightly divergent relation to each other, that is, at 65 an obtuse angle to each other, and that there

is sufficient rotation of the shaft 17 that when one pawl is thrown up in engagement with the teeth on the ratchet wheel, the other pawl is shifted downward out of engagement. Thus, for instance, in the movement 70 of the swing from one extremity of its arc to the other, one of the pawls will be depressed, which will throw up the other pawl into a position to engage with the ratchet teeth on that side of the ratchet wheel, and 75 upon a reverse movement of the swing, the first named pawl is thrown up and the second named pawl thrown down. The bar or cross piece 15 limits the rotation of the shaft 17, but this shaft has just sufficient 80 rotation to prevent one of the pawls engaging with the ratchet when the other pawl is engaged.

Having described my invention, what I claim is:—

1. The combination with a lawn swing including a supporting frame and an oscillatable body, of a fan shaft mounted upon the body, a ratchet wheel mounted upon the fan shaft and supported by the body, and oppositely directed pawls mounted upon the base and engageable with said ratchet wheel as the body is oscillated past it to thereby cause an intermittent rotation of the ratchet wheel in one direction.

2. The combination with a lawn swing including a base, standards extending upward from the base, and a body swingingly supported upon said standards, of a rock shaft mounted upon the base and having oppositely directed pawls having outwardly extending teeth at their ends, a ratchet wheel mounted upon the under face of the body and having radially directed teeth, a fan shaft mounted upon said body and engaged by the ratchet wheel, and a fan operated by said shaft, the movement of the body in one direction acting to engage one pawl to shift it out of operative position and shift the other pawl into operative position to engage with the teeth on that side of the ratchet wheel.

3. The combination with a lawn swing including a base, standards mounted thereon, and a body swingingly supported upon the standards, of a cross bar on the base, bearing members mounted on the cross bar, a rock shaft supported in said bearing members and having laterally, upwardly inclined pawls, each formed with an upwardly 120 extending tooth at its outer end, the outer end face of the tooth being beveled, a bushing extending through and mounted upon the bottom of the body, a shaft section passing through said bushing and rotating therein, antifriction bearings between the bushing and the shaft section, a ratchet wheel carried upon the lower end of the shaft section and having radially directed teeth, all of the teeth on one face being inclined and 125 130

being disposed to operatively engage said pawls alternately as the body is swung past the first named shaft, a fan shaft extending upward from said shaft section, and fan blades operatively connected to said last named fan shaft.

4. The combination with a lawn swing including a base, standards mounted thereon, and a body swingingly supported upon the standards, of a cross bar on the base, bearing members mounted on the cross bar, a rock shaft supported in said bearing members and having laterally, upwardly inclined pawls, each formed with an upwardly extending tooth at its outer end, the outer end face of the tooth being beveled, a bushing extending through and mounted upon the bottom of the body, a shaft section passing through said bushing and rotating therein, anti-friction bearings between the bushing and the shaft section, a ratchet wheel carried upon the lower end of the shaft section and having radially directed teeth, all of the teeth on one face being inclined and being disposed to operatively engage said pawls alternately as the body is swung past the first named shaft, the upper end of the shaft section being provided with a socket, a fan shaft detachably engaged with said socket, and a fan having a body and radial blades disposed on said fan shaft and vertically adjustable thereon, the blades of the fan being inclined to the plane of rotation of the fan.
5. The combination with a lawn swing including a base, standards mounted thereon, and a body swingingly supported upon the standards, of a cross bar on the base, bearing members mounted on the cross bar, a rock shaft supported in said bearing members and having laterally, upwardly inclined pawls, each formed with an upwardly extending tooth at its outer end, the outer end face of the tooth being beveled, a bushing extending

through and mounted upon the bottom of the body, a shaft section passing through said bushing and rotating therein, said shaft section at its lower end having a square portion and a threaded portion, a ratchet wheel detachably mounted upon the square portion of the shaft section and having radially disposed teeth, all of the teeth having faces inclined in the same direction, a nut engaging the threaded portion of the shaft section and holding the ratchet wheel in place, ball bearings disposed between said bushing and the ratchet wheel, said shaft section at its upper end being flanged and formed with a socket, ball bearings disposed between said flanged portion of the shaft and the adjacent portion of the bushing, a fan shaft detachably mounted in the socket, and a fan mounted on the shaft and having radially extending blades.

6. An attachment for lawn swings comprising bearing members, a rock shaft rotatably supported therein and having oppositely directed pawls disposed in divergent planes, each pawl having a tooth at its extremity, the outer end faces of the teeth being beveled, said bearing members being adapted to be attached to the base of a swing, a bushing adapted to be attached to the body of the swing, a fan shaft passing through said bushing and having a ratchet wheel detachably mounted on the lower end of the shaft, the wheel being provided with radially extending teeth having faces intersecting in the same direction and adapted to be engaged by the pawls, and a fan operatively mounted upon said shaft.

In testimony whereof I hereunto affix my signature in the presence of two witnesses.

JOHN GEHBAUER.
